1,924,316

METHOD OF MAKING DIAPHRAGMS

Jurjen S. High, Oaklyn Manor, N. J., assignor to
Westinghouse Electric & Manufacturing Com-
pany, a Corporation of Pennsylvania

No Drawing. Application July 30, 1930
Serial No. 471,751

2 Claims. (Cl. 154—2)

My invention relates to cone-speaker dia-
phragms, or the like, and more particularly to a
method of manufacturing the same whereby an
increase in the speed of production and an im-
provement in the uniformity of product may be
obtained.

According to the prior art, the method most
commonly employed in the manufacture of dia-
phragms from paper, cloth or the like comprises
10 first the preparation of a circular blank, then
cutting or punching therefrom a sector in the
form of a segment of the circle embracing ap-
proximately a 30° angle, and thereafter stitching
or glueing together the two edges of the blank
thus formed. This method results in a product
15 having a heavy stitched or cemented seam ex-
tending from the apex of the cone to its circum-
ference, thereby detracting measurably from the
appearance and uniformity of the article.

More important, however, is the fact that, be-
cause of the time involved in the performance of
the necessary steps in the manufacture of the
diaphragm, the above method does not lend it-
20 itself to rapid quantity production.

It is, accordingly, one object of my invention
to provide a method of manufacture for dia-
phragms which shall permit of quantity produc-
tion on an economic basis.

Another object of my invention is the provision
30 of a method of manufacturing cone-speaker dia-
phragms or the like whereby a product of uniform
quality may be obtained.

Another object of my invention resides in a
35 dry process for manufacturing diaphragms.

Another object of my invention lies in the pro-
vision of a simple and efficient method of pro-
ducing cone-speaker diaphragms or the like with
a negligible amount of waste and loss.

Another object of my invention is to provide a
40 method of preparing sheet material to adapt it
for the manufacture of diaphragms according to
my new method.

In a copending application of mine, Serial No.
45 468,830, filed July 18, 1930, I have set forth and
described a method of manufacturing loud-
speaker diaphragms of the cone-type which com-
prises slightly moistening a mixture of paper
pulp or the like and a binder having a certain
50 amount of plasticity, and subsequently operating
upon the mixture by means of a die of a novel
type so formed and constructed as to compress
the mass into its desired shape.

55 The present method to be described by me dif-
fers materially from the method described in the

above referred to application, in that the process
is inherently a dry process.

In the present process, one of my objects is to
manufacture loud-speaker diaphragms along the
lines followed in the manufacture of stamped
60 metal ware, a procedure which permits of rapid
production of the desired article.

Metals inherently possess a characteristic
which permits of their being stamped and dis-
torted into various shapes and configurations. 65
This characteristic is that property of the metal
which permits it to flow or stretch under the
application of forces of compression or tension.
The materials normally used in the manufacture
70 of cone diaphragms, however, do not possess this
desirable characteristic, and, consequently, so far
as I am acquainted with the prior art, no method
has been devised whereby diaphragms of the type
mentioned can be manufactured by methods cus-
75 tomarily applied to metal articles, wherein the
article to be manufactured is produced by flow-
ing or stretching the sheet material from which
it is made.

The problem may be solved by imparting to a
sheet of material to be used in the production of
80 a diaphragm the characteristic of stretching or
flowing under the application of pressure. In the
solution of the above problem, a sheet of sub-
stantially non-flowable material, such as paper,
cloth and the like, is operated upon to produce
85 irregularities in its structure. This may be done
by creping the material, by which means we may
condense the flat sheet of material within an
area smaller than that normally occupied by the
uncreped sheet, in which condition, the sheet is
90 adapted to be distorted into a plurality of shapes
without tearing or destroying its homogeneous
structure.

Crepe paper of the conventional type is normal-
ly produced by creping the paper in one direction
only, permitting a specific flow in one direction
of approximately 69%. However, to prepare a
blank sheet from which the diaphragms are to
be punched, it will be necessary to crepe the blank
95 in at least two different directions, so that the
permitted flow or stretch of the paper or mate-
rial in all directions will be substantially uni-
form.

It will be possible to obtain similar results by
embossing the paper or sheet material in such
manner that various figures, geometrical or oth-
erwise, appear on both sides of the sheet. It
will be apparent that sheet material embossed
in the manner described will possess the desired
105 quality whereby, by means of suitable dyes, these
110

sheets of material may be distorted into the desired shapes.

As an alternative method of preparing sheet material to impart thereto the characteristic of flowing under pressure, the sheet may be modified by corrugating it, the corrugations taking the form of concentric circles, etc. A configuration of this type will obviously permit of a uniform flow in all directions. The corrugations, prior to distorting the sheet into its final shape, may be of such depth that, during the distorting step, the corrugations will not be completely ironed out. This possesses the advantage of imparting to the final diaphragm a greater stiffness against paper rattle, thereby making unnecessary the concentric embossing usually employed in the manufacture of cone diaphragms, after the diaphragms have been formed.

Before the blank sheets of material are creped, they should have approximately the thickness desired in the finished diaphragm. The creped paper, known in the prior art and referred to heretofore as being creped in one direction only, besides being unsuitable for loud-speakers, because of its uni-directionally creped characteristic, also is not of the desired thickness, this paper having a thickness of approximately 3 mils when uncreped. The material to be used for diaphragms should have a thickness at least twice as great and should be creped in such manner as to permit a flow of approximately 40% in all directions.

It will be possible, however, to utilize a plurality of thin sheets super-imposed one upon another to produce a sheet of the required thickness. Between the various layers, a suitable binder may be employed to unify the sheets into an integral structure, the addition of an adhesive binder or some suitable sizing material being usually desirable. We prefer, however, a sheet material, such as dry-mounting tissue which is employed in photographic work for mounting purposes. This sheet material usually constitutes a gelatinized paper adapted, upon the application of heat, to acquire adhesive properties. This material may be creped in a manner similar to that of diaphragm material and inserted between the various layers thereof. Upon the application of the die to distort the resultant composite sheet into its finished form, heat may be applied in any suitable manner to bring about the unification of the various layers of material.

The various geometrical configurations imparted to the substantially flat sheet material prior to distorting the same into the shape of the finished product may or may not be of such depth as to be completely ironed out during the distorting process. By making the configurations of sufficient depth, it will be possible to produce a diaphragm, the surface of which will be covered by any suitable geometrical design, thereby improving the appearance of the finished article.

Throughout the above description, I have used

the expressions "creped" or "creping" in a generic manner as applying to all sheet material which has been condensed within an area less than that ordinarily occupied by the sheet.

In lieu of the creping operation for imparting the flow characteristic to a sheet of otherwise non-flowable material, I consider it within the scope of my invention to produce a suitable material of fibrous nature, the fibres of which have such characteristics either because of their length or the manner in which they are intermingled, that the material may be stretched or caused to flow, under the application of pressure, without being torn or otherwise destroyed.

After the distorting operation necessary to give the final shape to the material, the resulting product may be protected against atmospheric influences by applying thereto a finish having the desired properties. Aeroplane dope or pyroxylin lacquer may be suggested as materials having such properties as to afford protection to the diaphragm against atmosphere influences.

The process disclosed by me above does not employ the use of wet or moist material. It is a dry process from beginning to end, in view of which the time required to produce a finished article is materially shortened. The diaphragms are adapted to be punched from sheet material in much the same manner as the method used for quantity production of metallic articles. It will be apparent, therefore, that the objects of my invention have been met by the process described above.

Various modifications may be made within the scope of my invention which may have a wider field of application than that described above. While I have disclosed my process as applied to the manufacture of loud-speaker diaphragms, the same process may be employed in the manufacture of non-related articles, such as paper boxes, novelties, and the like which may generically be described as dished receptacles, wherein the shape of the completed article is such as to permit of being punched and pressed into completed form from a substantially flat sheet of material. I, therefore, do not desire to be limited to the details disclosed above, except insofar as is necessitated by the prior art and the appended claims.

I claim as my invention:

1. The method of making a dished article which comprises preparing a blank of substantially flat material, creping said blank in at least two directions to acquire the property of flowing substantially equally in all directions under the application of pressure and subsequently distorting said blank into its desired form.

2. The method of making a dished article which comprises creping a substantially flat sheet of material in at least two directions, maintaining said sheet in a substantially dry condition and subsequently distorting said sheet into its desired form.

JURJEN S. HIGH.
